INVENTOR.
Cecil Arthur Whitney

BY C. P. Goepel.

ATTORNEY.

UNITED STATES PATENT OFFICE.

CECIL A. WHITNEY, OF REMUERA, AUCKLAND, NEW ZEALAND.

DEVICE FOR USE IN PLAY OR PRACTICING CERTAIN GAMES, SUCH AS GOLF.

1,405,081.

Specification of Letters Patent. Patented Jan. 31, 1922.

Application filed April 17, 1920. Serial No. 374,576.

To all whom it may concern:

Be it known that I, CECIL ARTHUR WHITNEY, a subject of the King of Great Britain, residing at 40 Victoria Avenue, Remuera, 5 Auckland, in the Dominion of New Zealand, have invented certain new and useful Improved Devices for Use in Playing or Practicing Certain Games, such as Golf, of which the following is a specification.

10 This invention relates to an improved device for use in playing or practicing certain games, such as golf and refers especially to nets for stopping balls thrown by hand or struck by a club, bat or other propelling 15 agency.

The object of the invention is to provide a device having means whereby a ball or other object thrown or propelled with even moderate force against the same will be caught 20 and held at or near the point at which it struck.

I accomplish this object by providing a device which consists of a net or the like against which a ball is projected having 25 means at the back thereof whereby the ball is held in a pocket formed by a portion of the said net being carried on by the ball. The most convenient form of device for effecting this purpose comprises the combination of a net having a mesh through 30 which the ball can freely pass and a net or piece of textile material of smaller mesh than the diameter of the ball suspended in front of the first mentioned net whereby 35 when the ball is propelled against the front net or textile material it will carry a part thereof through a mesh in the rear net and form a pocket in which the ball will be held and the direction of flight thereby indicated.

The front net can be made the same length as or longer than the rear net to meet or overlap side or wing nets set at right angle or oblique angles to the main 45 double nets and a top net can be arranged to project forward (as a roof) from the top of the said main double net. The sides or wings form obstructions for badly aimed balls and they may comprise single or 50 double nets as preferred.

In this specification the term "ball" is intended to include a golf or other ball or object which when thrown at the net will carry a portion of the front net through the 55 rear net and form a pocket in which it will be supported.

In order that the invention may be readily understood reference will now be had to the accompanying sheet of explanatory drawings wherein:—

Figure 1 is a view in perspective of a device constructed in accordance with the invention, a central portion of the front net being shown broken away to more clearly show part of the rear net.

Figure 2 is a view in perspective of one corner of the device which shows clearly the arrangement of the nets and is drawn to a larger scale than Figure 1.

Figure 3 is a view in sectional side elevation of portions of the rear and front nets showing portion of the front net projecting through a mesh of the rear net and holding a ball.

Figures 4 and 5 are views in plan and 75 perspective of a modified arrangement of the nets and means for supporting the same.

In these drawings like characters of reference are employed to indicate the same or corresponding parts in the different views 80 and the letter *a* designates the rear net which is made of suitable size and has a mesh larger than the ball to be stopped by the device.

The said rear net is suspended from a 85 horizontal cord *b* which is stretched between two posts *c* which may be driven into the ground and stayed by guy ropes *d* and pegs *e* as shown in the drawings or form part of a suitable framework having an approved 90 supporting base.

The mesh of the rear net *a* preferably is made rectangular in shape and the sides thereof are set squarely, that is to say, they are arranged parallel to the cord *b* and 95 posts *c* but various other forms of mesh will be found more or less satisfactory in use.

The front net *f* is suspended from a cord *g* stretched horizontally between the posts *c* in front of the cord *b* and this net may 100 be of the same length as or longer than the rear net *a*.

The mesh of the front net *f* preferably is shaped in the form of a narrow diamond and the said net is hung with the longest 105 diagonal or acute angles of the mesh in a vertical line. Although the front net is described and illustrated as being formed with a diamond shaped mesh a net having a mesh of a different shape will provide a certain 110 amount of efficiency for the purpose for which it is used. The front net *f* is made

of much finer twine or cord than the rear net *a* to ensure it giving freely to the force of a ball *h* impelled against the same so, that it will be easily passed through a mesh 5 in the said rear net and form a pocket *i* in which the said ball will be held.

Side or wing nets *j* are arranged at right angles or at oblique angles to the main double nets *a* and *f* and the mesh of these 10 side or wing nets is made small enough to prevent a ball passing therethrough when projected thereagainst.

When the front net *f* is made longer than the rear net *a* its ends are arranged to 15 overlap parts of the side or wing nets *j* to prevent a ball passing through any opening between the meeting side edges of the main double nets and the said side or wing nets.

The side or wing nets *j* and the overlapping end portions of the front net *f* are 20 suspended from cords *k* and *l*, respectively, which are stretched between the posts *c* and *m*, the posts *m* being driven into the ground in advance of the former and stayed by 25 suitable guy ropes *n* and pegs *o* or they may form part of a supporting frame.

A top net *p* is arranged to project forward horizontally or at a suitable angle from the top of the main double nets *a* and 30 *f* and this said top net will prevent a badly aimed and rising ball passing over the said main double net.

The top net *p* is supported on cords *q* 35 stretched between the posts *c* and *m* and entirely covers the space bounded on three sides by the main double nets and the side or wing nets.

In lieu of arranging the main double nets *a* and *f* in a straight line as hereinbefore described and as shown in Figure 1 of the drawings they may be supported in a curve 40 as shown in Figures 4 and 5 of the drawings.

In Figures 4 and 5 of the drawings the 45 main double nets are shown supported on a curved bar of a frame *r* and in the former figure the dotted line *s* serves to indicate the front edge of a top net which is stretched over the frame to cover the space bounded 50 by the same.

The use of a curved supporting frame obviates the necessity of employing side nets as *j* but if preferred main double nets *a* and *f* can be suspended only from the centre 55 part of the frame and wing or side nets can be suspended from the end parts thereof.

In a modification of the invention (not shown in the drawings but which will be easily understood without the aid of illustrations) the rear net *a* may be made of wire 60 and suspended as hereinbefore described and a piece of fabric of suitable texture can be substituted for the front net *f*.

A device constructed as hereinbefore described will be found particularly useful

by golfers in practicing driving and other long distance shots as when a ball is driven into the net it will be caught and held at or near the point at which it struck the same and thereby serve to indicate the direction 70 of flight of the ball from the point at which it was hit with the club.

The ball is removed from the net by pulling the portion forming the pocket back through the mesh of the rear net or by inserting a finger through the nets below the pocket and pushing the ball and pocket part of the net forward through the mesh of the rear net.

The invention can be adapted for use in 80 various games as for instance the main double nets can be marked to serve as a target and a ball or other object thrown at the same will be caught and held at the point at which it struck and the accuracy or otherwise of the aim will be clearly registered.

The construction and arrangement of the nets and means for supporting the same shown in the drawings are those which have been found highly satisfactory in practice 90 but it will be obvious that any ordinarily intelligent person will be able to modify or rearrange the parts to suit particular requirements without departing from the spirit and scope of the invention and I 95 therefore do not wish to be understood as limiting myself to the precise constructions and arrangements herein before described.

I claim:—

1. A device for use in playing or practicing certain games consisting of a net or the like of such mesh or texture that a ball will pass freely therethrough and a net of small mesh suspended loosely in front of and close to the net of larger mesh, whereby when a 105 ball is projected against the loosely suspended net a portion thereof will be carried rearwardly through a mesh in the rear net to form a pocket to hold the ball.

2. A device for use in playing or practicing certain games comprising a stout net of large mesh, and a net of finer mesh made of soft material suspended in front of the first mentioned net whereby a ball propelled against the front net will carry part thereof 110 through a mesh in the rear net and form a pocket at that point to hold the ball.

3. A device for use in playing or practicing certain games comprising a stout net of large mesh suspended vertically between two 115 posts, wing nets of small mesh supported between posts at an angle to the ends of the first mentioned net, and a net of fine mesh suspended in front of the first mentioned net and having its ends overlapping part of the 120 wing nets as and for the purposes herein specified.

4. A device for use in playing or practicing certain games comprising a stout net of large mesh suspended vertically between two 125

- posts, wing nets of small mesh supported between posts at an angle to the ends of the first mentioned net, a net of finer mesh suspended in front of the first mentioned net 5 and having its ends overlapping part of the wing nets, and a top net supported above the space surrounded on three sides by the double nets and the wing nets as for the purposes herein specified.
- 10 5. A device for use in playing or practicing certain games comprising a stout net of large mesh suspended vertically between two posts and a piece of flexible textile material suspended in front and close to the net whereby a ball propelled against the textile 15 material will carry part thereof through a mesh in the net and form a pocket on the rear thereof to hold the ball.
6. A device for use in playing or practicing certain games comprising a rear net having a large rectangular mesh the sides of which are arranged horizontally and vertically, and a net of smaller mesh suspended in front of the first mentioned net and having a mesh formed in the shape of a narrow 20 diamond the said net being hung with the longer diameter of the mesh in a vertical line.
- In testimony whereof I have signed my name to this specification in the presence 25 of two subscribing witnesses.

CECIL A. WHITNEY.
